(57) **CLAIM**

I claim the ornamental design for a gutter downspout adapter,
substantially as shown and described.

DESCRIPTION

FIG. 1 is a perspective view of a gutter downspout adapter
showing my new design;

FIG. 2 is a front elevation view of the adapter of FIG. 1;

FIG. 3 is a rear elevation view of the adapter of FIG. 1;

FIG. 4 is a top plan view of the adapter of FIG. 1;

FIG. 5 is a bottom plan view of the adapter of FIG. 1;

FIG. 6 is a left side elevation view of the adapter of FIG. 1;

FIG. 7 is a right side elevation view of the adapter of FIG. 1;

FIG. 8 is a perspective view of a gutter downspout adapter
showing another one of my new designs;

FIG. 9 is a front elevation view of the adapter of FIG. 8;

FIG. 10 is a rear elevation view of the adapter of FIG. 8;

FIG. 11 is a top plan view of the adapter of FIG. 8;

FIG. 12 is a bottom plan elevation view of the adapter of FIG.
8;

FIG. 13 is a left side elevation view of the adapter of FIG. 8;
FIG. 14 is a right side elevation view of the adapter of FIG. 8;
FIG. 15 is a perspective view of a gutter downspout adapter
showing another one of my new designs;

FIG. 16 is a front elevation view of the adapter of FIG. 15;

FIG. 17 is a rear elevation view of the adapter of FIG. 15;

FIG. 18 is a top plan view of the adapter of FIG. 15;

FIG. 19 is a bottom plan view of the adapter of FIG. 15;

FIG. 20 is a right side elevation view of the adapter of FIG. 15;
and,

FIG. 21 is a left side elevation view of the adapter of FIG. 15.
In the drawings, the broken lines present features of the gutter
downspout adapter that form no part of the claimed design.
